HARLEY A. W. HOWCOTT, OF BATON ROUGE, LOUISIANA.

CLEANABLE TRAP FOR SINKS AND THE LIKE.

Application filed February 2, 1928. Serial No. 251,364.

This invention relates to traps for sinks, basins and the like, and more particularly to readily cleanable fixtures of this character.

It is well known that in fixtures of this character ordinarily used, a gooseneck or return bend therein has been found necessary to provide a water seal in the fixture to prevent foul odors and gases from backing up and entering the room where the fixture is located. These return bend fixtures, owing to their location, are difficult to clean, and are objectionable for the reason that they are subject to leakage incident to wear in the threads and washers employed in connection with the clean out plug.

A primary object of the invention is to eliminate these goosenecks or return bends in fixtures of this character, and while providing a straight pipe having readily accessible cleaning chambers, also so construct these chambers as to prevent all possibility of sewer gas backing up into the room and permits lost articles which may have dropped into the sink and entered the trap to be recovered without difficulty, and yet prevent all possibility of articles and sewage entering the sewer pipes and stopping them up.

Another object is to so construct a fixture of this character that sewer gas will be prevented from escaping into the room while the fixture is being cleaned.

Another object is to provide a fixture of this character composed of a plurality of readily separable parts which are so connected as to prevent all possibility of leakage while permitting ready disassembly for cleaning, repairs, and other purposes.

In carrying out these objects, the invention is susceptible of modification without departing from the spirit or sacrificing any of the advantages of the claimed invention; there being shown in the drawings for illustrative purposes a preferred and practical form, in which;

45 Figure 1 represents a front elevation slightly in perspective of a sink equipped with this improved fixture,

50 Fig. 2 is a vertical transverse section on a larger scale, taken on line 2-2 of Fig. 1,

Fig. 3 is a similar view taken on line 3-3 of Fig. 2,

Fig. 4 is a horizontal section taken on line 4-4 of Fig. 3,

Fig. 5 is a similar view taken on line 5-5 of Fig. 3,

Fig. 6 is a detail perspective view of one

of the hinge members used in mounting the trap door,

Fig. 7 is a similar view showing the trap door detached, 60

Fig. 8 is a vertical section showing a slightly different form of the invention applied, and

Fig. 9 is a transverse vertical section taken in a plane at right angles to that shown in Fig. 8. 65

In the form shown in Figs. 1 to 7, the fixture 10 embodying this invention is shown applied to a sink 1 between the outlet opening therein and the drain pipe 2, with which latter the fixture is connected by a coupling nut 3. The fitting 10, where it is connected with the sink 1 in the bottom of said sink, is equipped with a strainer 4 such as is ordinarily used in sinks and over which is designed to be placed a rubber stopper 5 having a metal ring 6 for applying and removing it. As shown, the strainer 4 is made removable, and rests on a supporting shoulder 7 formed in the side walls of the outlet of the sink. A union-joint couples a plate 8 with the sink and this joint is here numbered 9. The pipe 8 is designed to conduct the water, etc., from the sink 1 into container 11 which constitutes a part of the fixture 10. 70

The container 11 which may be of any desired contour, being here shown round with the pipe 8 threaded into an opening 12 formed in the circumference thereof, said container having flat rear and front faces 13 and 14, respectively, the front face 14 being in the form of a cap having a threaded flange for removable connection with the container, and between which and the container is mounted a gasket 15 to ensure a water-tight joint between these parts. Projecting radially from the cap 14 are a plurality of hand grips 16 which are designed to facilitate the removal and application of the cap. It is of course understood that this removable cap 14 affords access to the interior of the container 11, for purposes presently to be described. 85

Two chambers 17 and 18 are formed within the container 11, the chamber 17 surrounding the opening 12 to receive the water, etc., coming in from pipe 8, and which passes out through screened openings 17^a in the side walls of the chamber 17 into the chamber 18. These openings 17^a are located above the bottom of the chamber 17. Near the upper end of the chamber 18 in opposite side 90

walls thereof are formed screened outlets 19, through which the water passes from the chamber 18 into the body portion of the container 11 and from this container the water strained in the manner above set forth passes through pipe 20 into another container 30 located in a plane below the container 11 and into which the pipe 20 extends to a point about midway the height thereof.

10 The container 30 is preferably smaller than the container 11 and may be of any desired configuration, being here shown similar in shape to said container 11, and is provided with a flat rear wall 31 and a 15 similar front wall 32 made in the form of the removable cap having the flange 33 threaded onto the front of the container 30 and provided with a gasket 34 between it and the container to ensure a water-tight connection. This cap 32 has radiating handles 35 to facilitate its application and removal.

At the lower end of the pipe 20 within the container 30 is mounted a weighted balanced trap door 36 designed to normally 25 close the lower end of the pipe 20 and prevent gases from backing up through the fixture 10 when the cap 14 has been removed for any purpose.

This container 30 with the valve or trap door closed lower end of the pipe 20 is designed as a safety device and may or may not be used as is found desirable, its principal function being as a precaution against sewer gas passing out into the room when the cap 14 is off.

The trap door or valve 36 is shown in detail in Fig. 7 and is made in the form of a disk with a radially extending neck or shank 36 projecting from the perimeter thereof and from opposite side edges of which extend trunnions 38 designed to be journaled in bearings 40 carried by curved plates 41 fixed to the outer face of the pipe 20. A weight 42 is secured to the outer 40 end of the shank 37 and operates to retain the door 36 in closed position, it being understood of course that when water passes down through the pipe 20 and encounters this door 36 that it will swing downwardly 45 in the dotted line path shown in Fig. 3 and permit the water to pass out of the container 30 into the discharge pipe 43.

When the screw cap 14 is screwed tightly 55 on the container 11 with the gasket 15 located between these parts, a container which is water and gas-tight is ensured. The location of the openings 17^a and 19 in the chambers 17 and 18 which are protected by suitable screens, operate to hold the water at 60 a predetermined level in a manner similar to a gooseneck and provides an effective seal against any sewer gas passing up through this container. Should the container 11 or any of the chambers thereof become clogged, 65 they may be easily cleaned by unscrewing

the cap 14 and during this operation the trap door 36 will be closed as shown in Fig. 3 and prevent any possibility of sewer gas passing out into the room.

It will thus be seen that this fitting 10 70 will effectively prevent any stoppage of the main sewer and any stoppage in the fixture itself may be quickly removed by removing either the cap 14 or 32 or both, and after cleaning out the clogged portion, these caps 75 may be quickly replaced and the device will be ready for use.

In Figs. 8 and 9, a slightly different form of fixture is shown, the parts of which corresponds to those of the figures just above described being given the same numerals, except that the exponent "a" is used in connection with them. In this form of the invention, the container 11^a is similar in shape and construction to the container 11 80 of the other figures, except as regards the arrangement of the chambers therein. In this form, a straining chamber 44 is formed by means of two laterally spaced partitions 45 and 46 extending obliquely inward from 85 the curved side wall of the container at a point near its discharge opening 11^b with the free ends of said partitions terminating short of the opposed wall of the container and having one of them arranged below the 90 inlet opening of the container, a little to one side of the center thereof. Within this chamber 44 is formed a partition screen 47 located at one side of a partition 48 which 95 extends inwardly from the container side wall at a point opposite that from which the partitions 45 and 46 extend and is arranged between said partitions terminating 100 at a point slightly in advance of the screened transverse partition 47, a similar partition 105 47^a being formed on the other side of the partition 48. This arrangement of partitions 45, 46 and 48, together with the screened partitions 47 and 47^a provide three 110 chambers 44, 49 and 50, arranged substantially at the center of the container 11^a while another chamber 51, which may be termed the filtering chamber is arranged above the partition 45 and a discharge chamber 52 is located below the partition 46. It will thus 115 be seen that with this arrangement, water entering through the pipe 8^a into the container 11^a will part enter the chamber 51 and part the chamber 44 and after the chamber 51 is filled, it will flow over the upper 120 or free edge of the partition 45 into the chamber 44 and pass through the screened partition 47 into the chamber 49, and thence out through the screened partition 47^a into the chamber 50 from which it will overflow 125 partition 46 into the discharge chamber 52 and pass down through the pipe 20^a, the container 30^a to the main sewer. The water level is maintained at the point shown in Fig. 8 so as to ensure an effective seal against 130

the passage of gas and odors out of the container 11^a to the room. 45

The container 30^a is similar to the one shown and described in the other figures 5 and hence will not be described in detail in this connection. 5

Without further description it is thought 10 that the features and advantages of the invention will be readily apparent to those skilled in the art, and it will of course be understood that changes in the form, proportion and minor details of construction may be resorted to, without departing from the spirit and scope of the claimed invention. 15

I claim:—

1. A fixture of the class described comprising a truncated cylindrical fluid-tight receptacle having diametrically opposite openings in the periphery thereof to provide an inlet and an outlet therefor, a chamber formed in said receptacle and communicating with said inlet, another chamber surrounding said inlet chamber and spaced from the walls of the receptacle, screened 20 openings in the inlet chamber above the bottom thereof, similar openings in the other chamber at points above the openings in the first mentioned chamber, whereby a water seal is provided in said chambers in the 25 path of the material passing from the inlet to the outlet.

2. A fixture of the class described comprising a truncated cylindrical fluid-tight receptacle having diametrically opposite openings in the periphery thereof to provide inlets and outlets therefor, a chamber formed in said receptacle and communicating with said inlet, another chamber surrounding said inlet chamber and spaced 30 from the walls of the receptacle, screened openings in the inlet chamber above the bottom thereof, similar openings in the other chamber at points above the openings in the first mentioned chamber, whereby a water 35

seal is provided in said chambers in the path of the material passing from the inlet to the outlet, and a removable front face on said receptacle secured in fluid-tight relation thereto. 45

3. A fixture of the class described comprising a cylindrical container closed at its opposite ends and having oppositely disposed openings in the periphery thereof to provide an inlet and an outlet, spaced partitions extending obliquely from the inner 50 face of the perimeter of said receptacle and terminating short of the opposed wall thereof, another partition extending from said opposed wall between said first mentioned partition, a screened partition arranged transversely between said partition whereby a water seal is formed in the path 55 of the material entering through the inlet and passing out of the outlet. 60

4. A fixture of the class described comprising a cylindrical container closed at its opposite ends and having oppositely disposed openings in the periphery thereof to provide an inlet and an outlet, spaced partitions extending obliquely from the inner 65 face of the perimeter of said receptacle and terminating short of the opposed wall thereof, another partition extending from said opposed wall between said first mentioned partition, a screened partition arranged transversely between said partition 70 whereby a water seal is formed in the path of the material entering through the inlet and passing out of the outlet, the partition extending between the transversely spaced 75 partition terminating short of the opposed side wall of the receptacle and extending beyond the screened transverse partition.

Signed at Baton Rouge, in the parish of East Baton Rouge, and State of Louisiana 85 this 31st day of January, A. D. 1928.
